UNITED STATES PATENT OFFICE.

EMMET PLATTEN, OF GREEN BAY, WISCONSIN.

REFRIGERATING COUNTER.

Application filed April 9, 1928. Serial No. 268,692.

This invention relates to refrigerating counters.

Objects of this invention are to provide a novel form of refrigerating counter in which a depressed metal body portion is provided and is adapted to directly receive the food, and in which a refrigerating unit is held in metal to metal contact with the depressed metal food receiving member so as to provide for the chilling of the member by direct conduction, and to so construct the counter that a completely enclosing hood is provided which wholly covers the upper portion of the depressed member and prevents any possible circulation of air, thereby maintaining the air absolutely still within the counter and allowing a dense chilled blanket of air to accumulate in the depressed portion without any chance of circulation and consequently without any currents of chilled air being initiated within the enclosed counter.

This invention, therefore, has for its further object to provide a counter in which although the food is freely accessible nevertheless air currents are wholly prevented and the air is chilled to a low temperature in its lowest stratum, and that as the upper stratum of air are approached, the chilling becomes less and less, so that there is no frosting of the glass enclosing casing and consequently the food is always easily visible without any obstruction whatsoever to the clear view of the prospective purchaser.

A further object of this invention is to provide a conduction counter which is so constructed that no moisture can accumulate beneath the metal depressed portion with consequent freedom from any chance of bulging up, due to the formation of ice below the metal depressed portion.

An embodiment of the invention is shown in the accompanying drawings in which:

Figure 1 is a transverse sectional view through the counter corresponding to the line 1—1 of Figure 2;

Figure 2 is a longitudinal sectional view taken on the line 2—2 of Figure 1.

Referring to the drawings, it will be seen that the refrigerating counter comprises a body portion having side walls 1, end walls 2, and a bottom wall 3. These walls may be of any suitable material, such for instance, as wood or metal, and within the body portion, the depressed metal food re-

ceiving portion 4 is positioned. This food receiving portion is reinforced and carried at its side edges by the longitudinal wooden strips 5, and at its end edges by the transverse wooden strips 6, as shown in Figures 1 and 2.

The upper edge of the depressed metal portion 4 has turned over flanges 7, as is apparent from the drawings. Beneath this metal body portion a refrigerating unit 8 is positioned and is held in any suitable manner in metal to metal contact with the bottom of the body portion. A convenient way of holding this refrigerating unit in position is by means of the metal bottom portion 9 which is caused to clamp the refrigerating unit 8 in direct metal to metal to metal contact so that direct conduction is the mode whereby cooling is effected.

This refrigerating unit may be of any suitable form such for instance as shown in my prior Patent No. 1,552,949 of September 8, 1925, for refrigerating counters, and in my Patent No. 1,655,025 of January 3, 1928, for refrigerating counters.

The unit chosen for illustration is provided with a plurality of pipes or apertures 10 with which an inlet pipe 11 and an outlet pipe 12 communicate. If desired, the accessories for this refrigerating unit may be carried in the lower portion of the counter 85 below the bottom 3. Applicant has developed many forms of units and any form will operate with this counter.

The space between the depressed metal body portion and the outer walls is filled by a high grade thermal insulating material 13 which prevents any conduction of heat from the outside to the inside. Further, the upper portion of the counter is covered at its edges by means of the counter-like portion proper 14 which extends along its sides and ends, as is apparent from the drawings.

Yielding sealing gaskets 15 and 16 are positioned between the top plate 14 and the members 5 and 6 and also the members 1 and 2. This forms a complete air seal and prevents any circulation of air and any carrying of the moisture into the interior of the apparatus.

The top plate 14 is centrally cut out corresponding to the contour of the metal depressed portion 4.

The top of the counter is completely covered by a glass hood indicated generally by the reference character 17, so that there is no possible chance of cross air currents or 5 any air currents which will disturb the blanket of dense chilled air accumulating in the depressed body portion. The air naturally settles in this depressed body portion as it becomes dense and chilled and the cover 10 directly cooperates to avoid any disturbance of this blanket of sealed air.

Any suitable type of doors, such as indicated by the reference character 18, may be employed to provide access to the interior 15 of the counter and preferably these doors are also formed of glass to enhance the appearance of the device.

It will be seen that a novel form of refrigerating counter has been provided in 20 which a dense chilled air blanket covers the food entirely and also is guarded against external disturbances, such as cross air currents, so that it remains permanently in the depressed metal conducting body portion.

25 Further, it is to be noted that by means of this arrangement there is no circulation of chilled air within the counter and conse-

quently there is no possible chance of frosting of the glass cover.

Although the invention has been described 30 in considerable detail, such description is intended as illustrative rather than limiting as the invention may be variously embodied and as the scope of such invention is to be determined as claimed. 35

I claim:—

A conduction refrigerating counter including a body portion, a depressed food receptacle of heat contacting material in the body and spaced from the walls thereof, thermal 40 insulating material in the body between the walls thereof and the receptacle, a counter including a face plate resting upon the upper edges of the walls of the body and receptacle, and yieldable sealing gaskets between the face plate rail and the upper edges of the body and receptacle to form an air seal for preventing the circulation of air 45 within the body.

In testimony that I claim the foregoing 50 I have hereunto set my hand at Green Bay, in the county of Brown and State of Wisconsin.
